ROTARY EXPLOSION-ENGINE.

1,033,748.

Specification of Letters Patent.

Patented July 23, 1912.

Application filed November 9, 1907. Serial No. 401,402.

To all whom it may concern:

Be it known that I, EDWARD K. STANDISH, a citizen of the United States, and a resident of Waltham, in the county of Middlesex and 5 State of Massachusetts, have invented an Improvement in Rotary Explosion-Engines, of which the following description, in connection with the accompanying drawings, is a specification, like figures on the drawings representing like parts.

This invention relates to rotary or turbine explosion engines, whereby, among other desirable results, I obtain a cleaner mixture than in the usual two cycle gas engine, a 15 greater gas expansion, less back pressure, better cooling, a high speed make and break timing device, fewer and more accessible parts than in previous constructions, greater compactness, less vibration and lighter 20 weight per horse power.

In order that the principles of the invention may be clearly understood, I have disclosed a single type or embodiment thereof in the accompanying drawings, wherein—

25 Figure 1 is a vertical, transverse section taken through the charging piston and that portion of the casing adjacent thereto, on the line C—D, Fig. 3; Fig. 2 is a vertical, transverse section of the working piston and 30 that portion of the casing adjacent thereto on the line A—B, Fig. 3; and Fig. 3 is a view, partially in plan and partially in transverse section, of an engine constructed in accordance with my invention.

35 Referring specifically to the single type or embodiment of the invention herein selected for illustration, the shaft whereon the rotating parts are mounted is indicated at 1 in each of the figures, it being mounted in any 40 suitable manner for rotation in the casing or chamber 2, as, for example, upon supporting trusses or bridges 3, which are of such construction as not to interfere with the free circulation of air through the interior of 45 the casing. The casing or chamber 2 is herein represented as of generally cylindrical formation, and is preferably formed of upper and lower castings 4 and 4' (Fig. 1) which may be identical or substantially 50 so formed, being made if desired from the same casting. As indicated in Figs. 1 and 2, the casing sections 4 and 4' are provided along opposite lateral edges with longitudi-

dinally disposed recesses receiving therein suitable packing strips or bars 5, which accurately locate the casing members during the assembling of the parts and tightly pack the same.

In the present embodiment of my invention, I mount upon the shaft 1 for rotation therewith a charging or compression piston or rotor 6 (see Fig. 1) and a working or explosion piston or rotor 7 (see Fig. 2). Referring more particularly to Fig. 1, I provide at suitable points between the inner face of the casing and charging piston 6 suitable packing strips or bars 8, which herein are represented as carried in recessed portions of the said piston. The charging piston 6 need not be provided with a hub or arms to directly support the same upon the shaft 1, but may be suitably connected to the other rotating parts of the mechanism to travel therewith. The said piston, as represented in Fig. 1, is provided with concentric portions 9 and 10, herein shown as diametrically opposed, and with intermediate eccentric portions 11 and 12 between which and the inner wall of the casing 2 are formed charging chambers 13 and 14, to which the expansive mixture supplied from any suitable source is entered by means of inlet pipes 15 and 16. Between said inlets 15 and 16 and the peripheral wall of the compression piston I provide suitable abutments 17 and 18 adapted to co-act with the peripheral face of said piston to direct the charges of expansive mixture from the charging chambers 13 and 14 into the compression chambers 19 and 20, represented most clearly in 90 Figs. 2 and 3. As each abutment 17 and 18 is in this type of my invention represented as pivotally mounted in the casing 2 and as provided with suitable packing 21 and 22 upon those faces thereof contacting with the 95 casing and piston, if desired and preferably the ends of said abutments are suitably packed. Each of said abutments is normally inwardly sprung pressed by means of springs 23 and 24 suitably mounted upon 100 lugs carried by the casing and abutments respectively. Each abutment is herein provided with one or more openings 25 to permit the passage of the expansive mixture from the pipes 15 and 16 into charging 105 chambers 13 and 14. It will be apparent

that in this type of the invention the charges are admitted at substantially diametrically opposed points and that the said charging piston procures two charges simultaneously through approximately one quarter revolution thereof, and that it compresses through the balance of the half revolution the charges into the compression chambers 19 and 20, herein represented as substantially diametrically opposed. It will thus be apparent that the charges are compressed simultaneously in such manner as to practically equalize the pressure upon the surfaces of both the charging and the working pistons. It will be apparent that the leading face 26 of each abutment serves to direct the charges, as indicated by the arrow in Fig. 1, into the compression chambers 19 and 20, which, as illustrated in Fig. 3, are disposed in direct communication longitudinally of the casing. One object of my invention is to compress the charges in the compression chambers 19 and 20 and to maintain such compression therein without appreciable loss until such charges are ignited. While I may accomplish this result in various ways, in this embodiment of my invention, I provide (see Fig. 2) a suitable number of abutments 27, 28 pivotally mounted at 29 upon the working piston and preferably at diametrically opposite points, and also provide abutments 30, 31 pivotally mounted at 32 in the casing, the abutments 30, 31 being adapted to act as the leading face of the compression chambers 19 and 20 respectively during the compression of the charges therein, and are suitably packed at top, bottom and sides as shown, the abutments 27, 28 being adapted to act as the leading faces of said compression chambers when the charges are ignited, whereby the impact or motive force of the charges is directly received by said abutments 27, 28 and whereby the charges are retained under full compression but without appreciable loss in said chambers 19 and 20 until ignited. The number of abutments may vary according to the requirements of the particular type of engine. I may provide one or more abutments, but find that two or four give excellent results. It is also apparent that the number of casing abutments may be varied to suit the requirements of the particular engine. By the diametric disposition of the working piston abutments, an equal distribution of pressure upon the working piston is obtained, the piston being thus balanced at all times and side thrust being eliminated. Each abutment 27, 28 normally moves outward under centrifugal action. Preferably I provide also coiled springs 33 mounted upon spindles 34, which, in turn, are seated in lugs 35 projecting from the shaft bearing and in recessed portions 36 of the piston, the lead-

ing ends of said spindles co-acting with lugs upon the inner faces of said abutments 27, 28, as clearly represented in Fig. 2. If necessary, these spindles may, however, be fastened to abutments 27 and 28 and utilized to prevent too great outward pressure, or any other means, such as a tension spring between the abutment and piston, may be used, or a positive stop may limit the outward movement of the abutment. It will be apparent that said springs 33 are disposed at such point that they may be maintained cool by the currents of air passing through the hollow pistons and maintained in circulation by having one set of the piston arms inclined like a fan. Preferably, each abutment 27, 28 is packed at top and bottom as indicated at 37, suitable packing being also preferably provided upon the ends, as will be more fully hereinafter described. Each abutment 30, 31 is normally spring pressed inward by means of coiled springs 38 suitably mounted upon lugs provided upon the abutments and casing, suitable means being provided to adjust the tension of said springs as indicated at 39. Preferably also cushioning means are provided to absorb the shock of the outward movement of said abutments. For such purpose, I herein provide coiled springs 40 mounted upon studs 40' of any suitable material, as steel, fiber, hard rubber, or some suitable slightly yielding substance. If necessary these springs may be cooled by forcing air through the space behind the abutments 30 and 31 or in any other suitable manner and if desired a plunger may be employed cushioning the blow upon air or other fluid. The said abutments contact with said springs 40 during their outward movement, and preferably before the explosion occurs the lugs 40' rest on the studs 40'. The working piston 7 is substantially concentric throughout its periphery when the abutments 27, 28 are in retracted position. Normally the casing abutments 30, 31 are maintained in an inner or projected position in contact with the periphery of the working piston, so that their faces 41, 42 act as the leading walls of the compression chambers 19 and 20, in which position they permit compression of the charges to the desired degree. During the rotation of the working piston, each piston abutment 27, 28 periodically contacts with the casing abutments 30, 31, forcing the same radially outward as said piston abutments 27 and 28 move radially outward in advance of said compression chamber, thus displacing said casing abutments as the leading face of said compression chamber. This superseding by the piston abutments of the casing abutments as the leading face of said compression chambers is done without loss or with-

out appreciable loss of the compression in said chambers. At the moment of explosion of the charges in said compression chambers and until the discharge of the 5 spent gases through the exits 43, 44, the piston abutments 27 and 28 remain at their limit or outward radial movement, but upon their approach to the succeeding compression chamber are moved radially inward in 10 any suitable manner. For that purpose, I provide rods or rolls 45 mounted in the casing in any suitable manner and disposed in such relation to the said abutments that they move the same inwardly to the required 15 extent. Preferably, between the rods or rolls 45 and compression chambers 19 and 20, I provide suitable packing strips or bars 46. If desired, and as represented in Fig. 2, the rear end of the outer face of each piston 20 abutment is beveled inwardly, as shown at 57. The construction of the piston abutment is such that, as the rear end of the outer faces thereof pass the packing strips 46, they pass obliquely across or through 25 the compression chamber, the said abutments at the same time displacing the casing abutments 30 and 31 by cutward movement of the latter. The engaging faces of the piston and casing abutments are such as to 30 prevent the escape of any appreciable portion of the compressed charge between them.

It is apparent that any suitable number of charging pistons and working pistons 35 may be employed. For example, I may mount upon the shaft 1 one charging piston between two working pistons, or any other suitable arrangement and disposition of such pistons may be provided to suit the requirements of the particular case. The provision of a working piston having two diametrically opposed abutments co-acting 40 with the opposed compression chambers gives four blows per revolution of the shaft 1, or the equivalent of an eight cylinder, 45 four cycle engine. If a charging piston having a partition through its center be mounted between two working pistons and the working pistons be so keyed that the abutments of one have a lead of ninety degrees over the other, the equivalent of a sixteen cylinder, four cycle engine is provided, 50 with the advantage of a long leverage, a clean mixture, full expansion of the gases and less parts and lighter weight. The proportions of the parts are such as to obtain 55 the proper pressure of the expansive mixture in the compression chambers 19 and 20. Moreover, the volume of the chambers between each casing abutment 30 and 31 and 60 the exhaust passages 43 and 44 is much larger than the volume of the charging chambers 13 and 14 (see Fig. 1). In this manner, I obtain full expansion of the gases before they reach the exhaust passages 43 65 and 44.

Any suitable means for packing the parts may be provided. I prefer, however, to provide means, such as represented in Fig. 3, wherein annular flanges 46, 47 and 48 are mounted upon the charging and working pistons, being secured thereto by a suitable number of tie rods 49, certain of which may serve as the pivots of the piston abutments 27 and 28, being enlarged for that purpose, if desired. Each of the said annular flanges is provided with one or more annular grooves 50 upon its outer peripheral face, the projecting webs between said grooves being received in suitable annular grooves 51 provided in the inner face of the casing 2. In the compression chambers, shown at the right in Fig. 3, the groove adjoining the piston is formed in the wall of the casing. Since the casing abutments 17 and 18 are never forced outwardly by the 70 charging piston beyond the inner edge of the grooves 51, such abutments are at all times radially inside the outer limit of the flanges 46 and 47, thus an effective packing is secured and the necessity for extremely 75 fine work is eliminated. At the opposite or explosion end of the casing 2, the groove adjacent the working piston is formed in the annular flange to provide for the inward movement of the casing abutments 30 and 31, and for the inward movement of the piston abutments 27 and 28, which never move 80 radially inward beyond the inner limits of the walls of the said grooves 51 in the casing. Since the flanges 47 and 48 are provided with shouldered portions intermediate their inner and outer faces, which rotate in corresponding portions of the casing.

The charging or compression piston need 105 not be directly mounted upon the shaft 1, but may be supported wholly by the tie rods 49, as clearly indicated in Fig. 2. By this arrangement of parts, much weight is eliminated and space is given for a water or oil 110 pump inside the bearings, which may be provided upon a suitable casting to be bolted to the casing.

Suitable sparking plugs 52 (see Fig. 3) are provided in the compression chambers 115 19 and 20, the explosion occurring when the timer springs 53 (see Fig. 3) contact with the projections 54 provided upon the working piston.

Any suitable means may be provided for 120 oiling the parts. In Figs. 1 and 2, the casing is represented as provided at its upper portion with a boss 55 to receive an oil pipe, relief cocks, being provided at suitable points, as represented at 56. If desired, however, the oiling may be accomplished 125 through hollows formed through the pistons, permitting the oil to be thrown outward through centrifugal force. Any suitable cooling fluid may be employed.

Having thus described one type or embodiment of my invention, I desire it to be understood that although specific terms are employed, they are used in a generic and descriptive sense and not for purposes of limitation, the scope of the invention being set forth in the following claims.

Claims.

1. A single expansion explosion engine comprising a casing having a passage or chamber, and means to compress, ignite and permit the explosion of separate charges therein including a shaft mounted to rotate in said casing, a rotary working piston mounted upon said shaft, and a rotary compressor acting to compress the explosive charge in said casing between the wall thereof and the rotary compressor and into said passage or chamber, there being at all times unobstructed communication between the working piston and said rotary compressor.
2. A single expansion explosion engine comprising a casing having a passage or chamber, and means to compress, ignite and permit the explosion of separate charges therein including a shaft mounted in said casing, a working piston and compression means rotating with said piston and mounted upon said shaft, the compressing means acting to compress the explosive charge into said passage or chamber, there being at all times unobstructed communication between the compression means and the working piston.
3. A rotary explosion engine comprising a casing, a shaft mounted therein, a working piston mounted upon said shaft, said piston being provided with a face or faces adapted to utilize the rotative effect of the charge, and means to position said face or faces in advance of said charge or charges without enlarging the space occupied by said charge or charges.
4. A rotary explosion engine comprising a casing and a shaft mounted therein, a rotary working piston and compression means rotating with said piston and mounted upon said shaft, there being a firing chamber within said casing, in which the charges are separately compressed, ignited and expanded, said compression means compressing the charge directly into the firing chamber and against said working piston, and means for retaining said compression thereof in said firing chamber until fired.
5. A rotary explosion engine comprising a casing having a passage or chamber therein provided with charge ignition means, a shaft mounted to rotate in said casing, a working piston, and compression means rotating with said piston and mounted on said shaft, there being a firing chamber within said casing, said compression means compressing the charge directly into

the said first mentioned passage or chamber, said passage or chamber being at all times in unobstructed communication with said working piston.

6. A rotary explosion engine comprising a casing, a shaft mounted therein, a working piston, and compression means rotating with said piston and mounted upon said shaft, said compression means compressing the charge directly into the explosion chamber and against said working piston, a pivoted abutment or abutments carried by said working piston, there being provisions whereby the said abutment or abutments may be forced outwardly.

7. A rotary explosion engine comprising a casing, a shaft mounted to rotate therein, a working piston mounted upon said shaft, means to compress a charge or charges directly against said working piston, a pivoted abutment or abutments mounted upon and rotating with said piston, there being provisions whereby the abutment or abutments may be forced outwardly, and means within said casing to force said abutment or abutments inward at the proper time.

8. A rotary explosion engine comprising a casing, a shaft mounted for rotation therein, a working piston mounted for rotation with said shaft, a compression chamber being formed between said casing and piston, means to compress an expansive mixture in said chamber, an abutment rotatable with said piston and radially movable with respect thereto, and means to position said abutment as the leading wall of said compression chamber without appreciable loss of compression in said compression chamber.

9. A rotary explosion engine comprising a casing, a shaft mounted therein, a working piston mounted upon said shaft, a compression chamber being formed between said casing and piston, igniting means within said compression chamber, means to supply a compressed expansive mixture to said chamber, said working piston having an impact receiving abutment and means to position said abutment as the leading wall of said chamber and to ignite said mixture without appreciable loss of compression therein.

10. A rotary explosion engine comprising a casing, a shaft mounted for rotation therein, a working piston mounted for rotation with said shaft, a compression chamber being formed between said casing and piston, means to supply a compressed expansive mixture to said chamber, and abutments carried by said casing and piston respectively and adapted successively to form the leading wall of said compression chamber.

11. A rotary explosion engine comprising a casing, a shaft mounted for rotation there-

- in, a working piston mounted for rotation with said shaft, a compression chamber being formed between said casing and piston, means to supply a compressed expansive mixture to said chamber, a movable abutment mounted in the casing and adapted to form the leading wall of said compression chamber, said engine having provisions to displace said abutment.
12. A rotary explosion engine comprising a casing, a shaft mounted for rotation therein, a working piston mounted for rotation with said shaft, a compression chamber being formed between said casing and piston, means to supply a compressed expansive mixture to said chamber, a movable abutment mounted in the casing and adapted to form the leading wall of said compression chamber, and means movable with said piston to supersede said abutment as the leading wall of said compression chamber.
13. A rotary explosion engine comprising a casing, a shaft mounted for rotation therein, a working piston mounted for rotation with said shaft, a compression chamber being formed between said casing and piston, means to supply a compressed expansive mixture to said chamber, a movable abutment mounted in said casing and adapted to form the leading face of said compression chamber until a charge is compressed therein, and means movable with said piston to replace said abutment as the leading face of said chamber prior to ignition.
14. A rotary explosion engine comprising a casing, a shaft mounted for rotation therein, a working piston mounted for rotation with said shaft, a compression chamber being formed between said casing and piston, means to supply a compressed expansive mixture to said chamber, a movable abutment non-rotary with the piston, and adapted to form the leading face of said compression chamber, and an abutment carried by said working piston adapted to engage the movable abutment and to displace it from its position as the leading wall of said compression chamber.
15. A rotary explosion engine comprising a casing, a shaft mounted for rotation therein, a working piston mounted for rotation with said shaft, a compression chamber being formed between said casing and piston, means to supply a compressed expansive mixture to said chamber, and radially movable abutments carried by the casing and piston respectively and each adapted to form periodically the leading face of said compression chamber.
16. A rotary explosion engine comprising a casing, a shaft mounted for rotation therein, a working piston mounted for rotation with said shaft, a compression chamber being formed between said casing and piston, means to pass an expansive mixture extraneously of said piston into said chamber and to compress it therein, said working piston having an impact receiving abutment and means to position said abutment as the leading wall of said chamber without appreciable loss of compression therein.
17. A rotary explosion engine comprising a casing, a shaft mounted for rotation therein, a working piston mounted for rotation with said shaft, a compression chamber being formed between said casing and piston, means to pass an expansive mixture extraneously of said piston into said chamber and to compress it therein, movable members carried by said casing and piston respectively and adapted to act periodically as the leading wall of said compression chamber, and shock absorbing means for said members.
18. A rotary explosion engine comprising a casing, a shaft mounted for rotation therein, a working piston mounted for rotation with said shaft, a compression chamber being formed between said casing and piston, means to pass an expansive mixture extraneously of said piston into said chamber and to compress it therein, and movable abutments carried by said casing and piston respectively, the first mentioned abutment being adapted to act as the leading wall of the compression chamber during the compression of the charge therein, and the last mentioned abutment acting as such leading wall when the charge is ignited.
19. A rotary explosion engine comprising a casing, a shaft mounted for rotation therein, a charging piston and a working piston mounted upon said shaft for rotation therewith, a charging chamber being formed between said charging piston and casing, and an explosion chamber between said working piston and casing, said chambers being in direct communication, an abutment rotatable with said working piston, and means to position it as the leading wall of said compression chamber.
20. A rotary explosion engine comprising a casing, a shaft mounted for rotation therein, a charging piston and a working piston mounted upon said shaft for rotation therewith, a charging chamber being formed between said charging piston and casing and an explosion chamber being formed between said working piston and casing, an abutment rotatable with said working piston, and means to advance said abutment from the rear of said compression chamber to the front thereof while maintaining the compression in said chamber.
21. A rotary explosion engine comprising a casing, a shaft mounted for rotation therein, a charging piston and a working piston mounted upon said shaft for rotation therewith, a charging chamber being formed between said charging piston and casing, and an explosion chamber between said working

- 5 piston and casing, said chambers having at all times free and open communication, an abutment carried by said casing and adapted to act as the leading face of said compression chamber during the compression of the charge therein, and an abutment carried by said working piston and adapted to act as the leading face of said compression chamber when the charge is ignited.
- 10 22. A rotary explosion engine comprising a casing, a shaft mounted for rotation therein, a charging piston and a working piston mounted upon said shaft for rotation therewith, a charging chamber being formed between said charging piston and casing, and an explosion chamber between said working piston and casing, pivoted abutments carried respectively by the chamber and the working piston, said abutments being adapted to act periodically as the leading face of said explosion chamber.
- 15 23. A rotary explosion engine comprising a casing, a shaft mounted for rotation therein, a charging piston and a working piston mounted upon said shaft for rotation therewith, a charging chamber being formed between said charging piston and casing and an explosion chamber between said working piston and casing, spring pressed movable abutments being mounted respectively upon said casing and working piston, said abutments being adapted to act periodically and successively as the leading face of said explosion chamber.
- 20 24. A rotary explosion engine comprising a casing, a shaft mounted for rotation therein, a charging piston and a working piston mounted upon said shaft for rotation therewith, a charging chamber being formed between said charging piston and casing and an explosion chamber between said working piston and casing, spring pressed movable abutments being mounted respectively upon said casing and working piston, said abutments being adapted to act periodically and successively as the leading face of said explosion chamber, and cushioning means for the abutments.
- 25 25. A rotary explosion engine comprising a casing, a shaft mounted for rotation therein, a charging piston and a working piston mounted upon said shaft for rotation therewith, a charging chamber being formed between said charging piston and casing and an explosion chamber between said working piston and casing, a movable abutment carried by the working piston, means tending normally to move said abutment outward, means in the rear of said explosion chamber to force said abutment inward, and an abutment carried by said casing and adapted to act periodically as the leading face of said explosion chamber.
- 30 26. A rotary explosion engine comprising a casing, a shaft mounted for rotation therein,
- 5 piston and casing, said chambers having at all times free and open communication, an abutment carried by said casing and adapted to act as the leading face of said compression chamber during the compression of the charge therein, and an abutment carried by said working piston and adapted to act as the leading face of said compression chamber when the charge is ignited.
- 10 22. A rotary explosion engine comprising a casing, a shaft mounted for rotation therein, a charging piston and a working piston mounted upon said shaft for rotation therewith, a charging chamber being formed between said charging piston and casing and an explosion chamber between said working piston and casing, a pivoted abutment carried by said working piston, a spring tending normally to force the same outward, means carried by said casing and in the rear of the explosion chamber to force said abutment inward, and an abutment carried by said casing and adapted periodically to form the leading face of said explosion chamber.
- 15 27. A rotary explosion engine comprising a casing, a shaft mounted for rotation therein, a charging piston and a working piston mounted upon said shaft for rotation therewith, a charging chamber being formed between said charging piston and casing and an explosion chamber between said working piston and casing, a pivoted abutment mounted upon said working piston, means tending normally to force the same outward, fixed means carried by said casing and adapted to force the abutment inward in the rear of the explosion chamber, and a pivoted abutment carried by the casing and adapted periodically to form the leading face of said explosion chamber.
- 20 28. A rotary explosion engine comprising a casing, a shaft mounted to rotate therein, a working piston mounted upon said shaft to rotate therewith, a compression chamber being formed between said piston and casing, means to compress a charge in said chamber, a plurality of impact receiving abutments carried by said piston, and means for placing said abutments simultaneously in operative position for firing with respect to said chambers without appreciable loss therein.
- 25 29. A rotary explosion engine comprising a casing, a shaft mounted therein, a working piston and compression means rotating with said piston and mounted upon said shaft, a compression chamber being formed within said casing, said working piston having an impact receiving abutment or abutments, and means to position said abutment or abutments as the leading wall or walls of said compression chamber and to ignite said charge before appreciable loss of compression therein.
- 30 30. A rotary engine comprising a casing, a shaft mounted therein, a piston mounted upon said shaft and having an internal air passage, one or more movable abutments carried by said piston, and a spring pressed spindle or spindles actuating said abutment or abutments, said springs being located in said air passage.
- 35 31. A rotary explosion engine comprising a casing, a shaft mounted to rotate therein, a charging piston and a working

piston mounted upon said shaft to rotate therewith, and means whereby a plurality of charges may be simultaneously compressed by said charging piston at points 5 equalizing the pressure upon the surface of said piston, a plurality of abutments carried by said working piston, and means to position said abutments in advance of the compressed charge without appreciable loss of compression.

10 32. A rotary explosion engine comprising a casing, a shaft mounted to rotate therein, a charging piston and a working piston mounted upon said shaft to rotate therewith, 15 and means whereby a plurality of charges may be simultaneously compressed by said charging piston directly into the firing chamber at points equalizing the pressure upon the surface of both pistons, abutments 20 carried by said casing and against which said charges may be compressed, and a plurality of abutments carried by said working piston and adapted to receive the motive force of said charges when ignited.

25 33. A rotary explosion engine comprising a casing, a shaft mounted to rotate therein, a charging piston and a working piston mounted upon said shaft to rotate therewith, and means whereby a plurality of charges 30 may be simultaneously compressed by said charging piston at points equalizing the pressure upon the surface of said piston, movable abutments carried by said casing and against which said charges may be 35 compressed, and a plurality of movable abutments carried by said working piston and adapted to replace said casing and to receive the impact of said charges when ignited.

40 34. A rotary explosion engine comprising a casing, a shaft mounted to rotate therein, a charging piston and a working piston mounted thereon to rotate therewith, means whereby the charging piston procures two charges simultaneously through substantially 45 one quarter revolution thereof and compresses said charges through substantially one quarter of said revolution, a pair of oppositely disposed compression chambers being provided into which said charges 50 are simultaneously compressed, a plurality of abutments carried by said working piston, and means to retain the compression in said compression chambers until the said abutments reach a position in advance 55 thereof.

60 35. A rotary explosion engine comprising a casing, a shaft mounted to rotate therein, a charging piston and a working piston mounted thereon to rotate therewith, means whereby the charging piston procures two charges simultaneously through substantially one half revolution thereof and compresses said charges through the balance of said revolution, a pair of oppositely disposed compression chambers be-

ing provided, into which said charges are simultaneously compressed, a plurality of abutments carried by said working piston, and means to retain the compression in said compression chambers until the said abutments reach a position in advance thereof, and means for simultaneously exploding and exhausting the two charges.

70 36. A rotary explosion engine comprising a casing, a shaft mounted for rotation therein, a working piston and a charging piston mounted thereon for rotation therewith, and one or more abutments carried by said casing and adapted to coöperate with said charging piston to direct the charge or 75 charges to the point or points of compression in operative relation to said working piston, said abutment or abutments having a passage therein for the entry of the charges to be compressed.

80 37. A rotary explosion engine comprising a casing, a shaft mounted for rotation therein, a working piston and a charging piston mounted thereon for rotation therewith, a compression chamber being formed between 85 said casing and said working piston, an abutment carried by said working piston and adapted to receive the impact of the charge in said compression chamber when ignited, and an abutment carried by said 90 casing and coöoperating with the charging piston and having a passage therein for the entry of the charge to be compressed.

95 38. A rotary explosion engine comprising a casing, a shaft mounted for rotation therein, a working piston and a charging piston mounted thereon for rotation therewith, a compression chamber being formed between said casing and said working piston, a movable abutment carried by said working piston, and a movable abutment carried by said casing, and each adapted periodically to 100 form the leading face of said compression chamber, and an abutment carried by said casing and adapted to coöperate with the 105 charging piston, said abutment having a passage or passages therein for the entry of the charge.

110 39. A rotary explosion engine comprising a casing, a shaft mounted for rotation therein, a working piston and a charging piston mounted thereon for rotation therewith, a compression chamber being formed between said casing and said working piston, a movable abutment carried by said working piston, and a movable abutment carried by 115 said casing, said abutments being adapted periodically and successively to form the leading face of said compression chamber, and a movable abutment coöoperating with 120 said charging piston and having a passage therein for the entry of the explosive charge.

125 40. A rotary explosion engine comprising a casing, a shaft mounted therein, a working piston and a charging piston mounted 130

upon said shaft, said pistons being at all times in open fluid communication, detachable flanges being provided upon said pistons, and means for securing said flanges in position.

41. A rotary explosive engine comprising a casing, a shaft mounted for rotation therein, a charging piston and a working piston mounted upon said shaft, said pistons having annular flanges 46, 47 and 48 mounted thereon, and tie rods 49 for securing said flanges in position, said flanges and the inner face of said casing being provided with grooves 50 and 51.

42. A rotary explosion engine comprising a casing, a shaft mounted to rotate therein, a charging piston and a working piston mounted to rotate with said shaft, said pistons having at all times free and open fluid communication and means whereby such charging piston may simultaneously procure and simultaneously compress two or more charges, and whereby said working piston may simultaneously receive two or more explosions and simultaneously exhaust two or more explosions.

43. A rotary explosion engine comprising a casing, a shaft to rotate therein, a charging piston and a working piston rotating with said shaft, there being at all times an open fluid communicating passage between said pistons, means permitting in said communicating passage but a single compression, ignition and expansion of each charge, and means for securing balancing of both pistons at all times.

44. A rotary explosion engine comprising a casing, a shaft mounted to rotate therein, a charging piston and a working piston mounted upon said shaft and rotatable therewith, said pistons being at all times in open fluid communication, said charging piston compressing separate charges for separate ignition and expansion, and means for maintaining said pistons balanced at all times.

45. A rotary explosion engine of the single expansion type comprising a casing, chambers being formed within said casing, a shaft mounted in said casing, a working piston mounted upon said shaft, means to secure and to maintain normal maximum compression of a separate charge in said chambers before and during the positioning of the operative portion of the piston head in advance thereof, means permitting but a single expansion of each charge, and means for balancing said piston at all times.

46. A rotary explosion engine of the single expansion type comprising a casing, a shaft mounted to rotate therein, a working piston, and compression means rotating with said piston and mounted upon said shaft, there being a firing chamber or cham-

bers within said casing, and separate ignition means within said chamber, means for compressing a charge or charges directly in said firing chamber or chambers, means permitting but a single expansion of each charge, and means for maintaining said rotating members balanced at all times.

47. A rotary engine driven by an expansive charge and comprising a casing, a piston mounted therein, means for balancing said piston at all times, a face or faces upon said piston being adapted to utilize the rotative power of the charge, and means to position said face or faces in advance of said charge or charges without enlarging the space occupied by said charge or charges.

48. A rotary engine driven by an expansive charge comprising a casing, a shaft mounted to rotate therein, a piston mounted upon said shaft, a chamber or chambers being formed within said casing, means to supply a compressed expansive charge or charges to said chamber or chambers, a pivoted abutment rotatable with said piston, and means to position said abutment as the leading wall of said chamber without appreciable loss of compression.

49. A rotary explosion engine comprising a casing, a shaft mounted therein, a working piston mounted upon said shaft, an explosion chamber within said casing, and means to compress a charge directly into said chamber, said piston having detachable annular flanges secured to its ends for the purpose of construction or packing.

50. A rotary engine comprising a casing and a working piston rotating therein and having supporting arms, said arms being inclined to the axis of the piston and the interior thereof being openly constructed to provide an air passage, through which air may be forced, a spring or springs carried by said piston and within the air passage, and a movable abutment or abutments within said casing and operated by said spring or springs.

51. A rotary engine, driven by an expansive charge, and comprising a casing, a shaft mounted therein, a piston mounted upon said shaft, a chamber or chambers within said casing, means to supply a compressed expansive charge or charges to said chamber or chambers, a pivoted abutment rotatable with said piston, and means to position said abutment as the leading wall of said chamber without appreciable loss of compression, said piston and casing being constructed to allow free internal passage of a cooling current.

52. A rotary explosion engine comprising a casing, a single shaft mounted for rotation therein, a charging piston and a working piston mounted upon said shaft and in fluid communication, means for fully com-

pressing a charge directly into the firing chamber, said working piston having a face which during compression forms one side of said firing chamber, there being uninterrupted communication at all times between said compression means and said working piston.

53. A rotary explosion engine comprising a casing, a single shaft mounted for rotation therein and a charging piston mounted upon and rotating with said shaft within said casing, said piston having approximately one half its periphery concentrically disposed and of greatest radius with respect to said shaft, and the remainder being eccentric to said shaft, so that substantially one half revolution is employed for suction and one half for compression.

54. A rotary explosion engine comprising a casing, a single shaft mounted for rotation therein, a charging piston and a working piston mounted upon and rotating with said shaft and in fluid communication, the periphery of said charging piston being concentrically and eccentrically disposed with respect to said shaft, said concentric portion having the greater radius.

55. An explosion engine comprising a casing, a single shaft mounted for rotation therein, a working piston and a charging piston mounted upon said shaft and rotating together and in fluid communication, the periphery of said charging piston being concentrically and eccentrically disposed with respect to said shaft, said concentric portion being adapted by its rotation to close and open casing ports.

56. A rotary explosion engine comprising a casing, a single shaft mounted for rotation therein, a charging piston mounted upon and rotating with said shaft within said casing, said piston having approximately one half its periphery concentrically disposed with respect to said shaft, and the remainder being eccentrically disposed, said concentric portion by its rotation closing and opening the casing ports.

57. A rotary explosion engine comprising a casing, a shaft mounted to rotate therein, a charging piston and a working piston mounted upon said shaft, gates in contact with said charging piston, the periphery of said charging piston having long and short concentric radii whose connecting inclines are sufficiently gradual to allow constant contact of the gate ends and also rotation in

either direction and the periphery of the working piston having a substantially radial shoulder.

58. A rotary engine comprising a casing, a shaft mounted therein, a working piston mounted upon said shaft, one or more movable abutments rotating with said piston, a spring or springs positioned within said casing and adapted to operate upon said abutment or abutments, and means to circulate a cooling fluid in effective cooling relation with said springs.

59. A rotary explosion engine comprising a casing, a shaft mounted therein, a working piston and compression means rotating with said piston and mounted upon said shaft, co-operating compression means independent of said shaft, a compression chamber being formed in said casing, said working piston having an impact receiving abutment or abutments, and means to position said abutment or abutments as the leading wall or walls of said compression chamber without appreciable loss of compression therein.

60. A rotary explosion engine comprising a casing, a shaft mounted therein, a working piston and compression means rotating with said piston but directly carried by said shaft, a compression chamber being formed in said casing, said working piston having an impact receiving abutment or abutments, and means to position said abutment or abutments as the leading wall or walls of said compression chamber without appreciable loss of compression therein.

61. In a rotary explosive engine, cylinders, a compression piston and an actuating piston connected to revolve as a unit and arranged in the respective cylinders, the compression piston having an eccentrically arranged peripheral compression pocket, and the actuating piston having an expansion pocket of like construction and arrangement, a firing chamber in communication with the cylinder of the actuating piston, and means to control the passage of each charge from the compression pocket to the expansion pocket through the firing chamber.

In testimony whereof I have signed my name to this specification in the presence of two subscribing witnesses.

EDW. K. STANDISH.
